(57) **CLAIM**

The ornamental design for a running vest, as shown and described.

DESCRIPTION

FIG. 1 is a front perspective view of a running vest showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is bottom plan view thereof.

The broken lines depict portions of the running vest and form no part of the claimed design.

1 Claim, 8 Drawing Sheets
